CLAIM

The ornamental design for a children's bed, substantially as shown and described.

DESCRIPTION

FIG. 1 is a front right side perspective view of children's bed, showing my new design;

FIG. 2 is a front elevational view thereof;

FIG. 3 is a rear elevational view thereof;

FIG. 4 is a right side elevational view thereof;

FIG. 5 is a cross-sectional view thereof taken on line 5—5 of FIG. 4; and

FIG. 6 is a top plan view thereof.

The left side elevational view, although not shown, is a mirror image of FIG. 4.

Fig. 1.

Fig. 2.

Fig. 3.
